[57] CLAIM

The ornamental design for a pendant, substantially as shown and described.

DESCRIPTION

FIG. 1 is a front elevational view of a pendant showing my new design.

FIG. 2 is a right side elevational view thereof.

FIG. 3 is a left side elevational view thereof.

FIG. 4 is a rear elevational view thereof.

FIG. 5 is a top plan thereof, and

FIG. 6 is a bottom plan thereof.

For convenience of illustration, the ring loops have been omitted from FIGS. 3-6.

FIG. 1

FIG. 2

FIG. 3

FIG. 4

FIG. 5

FIG. 6
